UNITED STATES PATENT OFFICE.

GEORGE P. YOUMANS, OF GALESBURG, MICHIGAN, ASSIGNOR TO THE
KALAMAZOO TANK & SILO COMPANY, OF KALAMAZOO, MICHIGAN.

SILO.

No. 854,010.

Specification of Letters Patent.

Patented May 21, 1907.

Application filed October 18, 1906. Serial No. 339,501.

To all whom it may concern:

Be it known that I, GEORGE P. YOUMANS, a citizen of the United States, residing at Galesburg, county of Kalamazoo, State of Michigan, have invented certain new and useful Improvements in Silos, of which the following is a specification.

This invention relates to improvements in silos.

10 The objects of this invention are, first, to provide in a silo an improved door frame construction. Second, to provide in a silo made up of sections an improved means for securing the sections together. Third, to 15 provide in a silo an improved door securing means. Fourth, to provide in an improved silo an improved construction and arrangement of the parts whereby the maximum strength of the material used is secured, 20 thereby enabling the employment of comparatively light material.

Further objects, and objects relating to structural details, will definitely appear from the detailed description to follow.

25 I accomplish the objects of my invention by the devices and means described in the following specification.

The invention is clearly defined and pointed out in the claims.

30 A structure embodying the features of my invention is clearly illustrated in the accompanying drawing, forming a part of this specification, in which,

Figure 1 is a detail elevation of a structure 35 embodying the features of my invention.

Fig. 2 is a detail elevation looking from the left of Fig. 1. Fig. 3 is a plan only, the wall staves at each side of the door-opening being shown. Fig. 4 is an enlarged elevation, 40 showing structural details. Fig. 5 is an elevation view looking from the left of Fig. 4, showing details of the construction or coupling for the silo wall sections. Fig. 6 is a detail elevation showing further structural 45 details. Fig. 7 is a vertical section taken on a line corresponding to line 7—7 of Fig. 6.

40 Figs. 8 and 9 are enlarged details showing the relation and connection for the cross pieces 3 and the vertical angle iron casing strips 2. Fig. 10 is a side elevation of one of the door latches 15. Fig. 11 is a plan thereof. Fig. 50 12 is an inverted plan thereof.

In the drawing, the sectional views are taken looking in the direction of the little ar-

rows at the ends of the section lines and similar reference characters refer to similar parts throughout the several views.

Referring to the drawing, 1—1 are vertical body or wall staves, only those at each side of the door-opening being shown. The 60 door-opening, as usual in silos, extends from the top to the bottom of the silo, the doors being made up of sections. On the inner edges of the staves 1 are angle iron plates 2, these plates being arranged with their angles 65 outward to overlap the edges of the staves, as is illustrated.

Across the door-opening, at intervals, are bars 3 also preferably formed of angle iron, the top bar of each section being arranged 70 with the angle upward and the bottom bar with the angle downward, as clearly appears in Figs. 1, 2, 4 and 5. The transverse bars 3 are riveted or bolted to the casing bars 2 by suitable rivets, as 5, and also to the staves 1 75 by bolts 6. To further strengthen the silo and prevent compression by the hoops 8, tongues or lugs 4 are punched inwardly on the bars 3 to engage the inside of the door casing irons 2. I thus secure great strength 80 for the weight of the material used.

To relieve the staves 1 as much as possible from the strain of the bolts 6, I preferably provide the same with bushings 7; see Fig. 7. The hoops 8 are preferably arranged about 85 the silo so as to embrace the cross pieces 3 so that they more effectively resist the compression strain of the hoops. It will be readily appreciated that this sometimes prevents very great strain owing to the swelling of the 90 staves.

I preferably construct my improved silo of horizontal sections, as stated; this enables their being assembled at the factory and quickly erected. This also enables the extension or addition to a silo should it be desired to do so. To accomplish this the staves 1 are preferably provided with dowel mortises 11 in each end in which are inserted the dowel plates 10; see Figs. 3 and 5. The 95 bolts 6 for securing the cross pieces 3 to the staves 1 are arranged through these dowel plates.

As previously stated, the top cross piece of each section is arranged with its angle iron 100 upward and the bottom cross piece of each silo section with its angle downward. This brings the horizontal legs of the cross pieces

together, as clearly appears in Figs. 4 and 5. These meeting cross pieces are secured together by the bolts 9 arranged therethrough.

Additional dowel plates 10 may be provided about the silo but as the arrangements will be readily understood, they are not here illustrated.

The doors are preferably made up of vertical side rails 12 to which the boards 13 are secured. Each door is provided with a pair of pivoted latches 15 having cam-shaped engaging portions 17 so that they draw the doors into place under tension.

The handle portions 18 of the latches are adapted to serve as ladder steps coacting with the cross pieces 3 to form a ladder. The latches are pivoted to the door side pieces by bolts 16, the engaging portions being adapted to engage the casing angle irons, as clearly appears in Fig. 1. Each latch is provided with a stop lug 19 adapted to support the same in a horizontal position when closed and also to limit its upward movement. Stop plates 20 are provided on the side pieces of the door; see Fig. 1.

By arranging the parts as I have illustrated and described, I secure a silo which is simple in construction and may be made up of comparatively light material and at the same time one which possesses great strength.

The structure may be readily put up in sections and the sections quickly assembled in erecting a silo. The doors are preferably provided with gaskets 14 and 21, but this, I am aware, is a common expedient.

I have illustrated and described my improved silo in detail in the form preferred by me on account of its structural simplicity and economy and convenience in use. I am, however, aware that it is capable of considerable variation in structural details without departing from my invention.

Having thus described my invention, what I claim as new and desire to secure by Letters Patent is:

1. A silo, comprising a plurality of wall sections, vertically arranged staves at the sides of the door-opening of each section, said staves having mortises in the ends thereof; vertical angle-iron casing strips arranged upon the inner edges of said staves with their angles outward; angle-iron cross-pieces arranged across the door-opening of each wall section and riveted to said casing irons, each wall section having a cross-piece at the top and bottom thereof, the bottom cross-piece being arranged with its angle downward, and the top cross-piece being arranged with its angle upward, so that the outwardly projecting legs of the adjacent cross-pieces are brought together; rivets arranged through the said outwardly projecting legs of the top and bottom cross-pieces of adjacent wall sections; lugs punched in from said cross-pieces to engage the inner sides of said cross-pieces to engage the inner sides of

said casing strips; dowel plates arranged in said mortises in the ends of said staves; bolts arranged through said cross-pieces, staves and dowel-plates; and hoops for wall sections arranged to embrace said cross pieces, as specified.

2. A silo, comprising a plurality of wall sections, vertically arranged staves at the sides of the door-opening of each section, said staves having mortises in the ends thereof; vertical angle-iron casing strips arranged upon the inner edges of said staves with their angles outward; angle-iron cross-pieces arranged across the door-opening of each wall section and riveted to said casing irons, each wall section having a cross-piece at the top and bottom thereof, the bottom cross-piece being arranged with its angle downward, and the top cross-piece being arranged with its angle upward, so that the outwardly projecting legs of the adjacent cross-pieces are brought together; rivets arranged through the said outwardly projecting legs of the top and bottom cross-pieces of adjacent wall sections; dowel plates arranged in said mortises in the ends of said staves; bolts arranged through said cross-pieces, staves and dowel plates; and hoops for wall sections arranged to embrace said cross-pieces, as specified.

3. A silo, comprising a plurality of wall sections, vertically arranged staves at the sides of the door-opening of each section; vertical angle-iron casing strips arranged upon the inner edges of said staves with their angles outward; angle-iron cross-pieces arranged across the door-opening of each wall section and riveted to said casing irons, each wall section having a cross-piece at the top and bottom thereof, the bottom cross-piece being arranged with its angle downward, and the top cross-piece being arranged with its angle upward, so that the outwardly projecting legs of the adjacent cross-pieces are brought together; rivets arranged through the said outwardly projecting legs of the top and bottom cross-pieces of adjacent wall section; lugs punched in from said cross-pieces to engage the inner sides of said casing strips; and hoops for wall sections arranged to embrace said cross-pieces, as specified.

4. A silo, comprising a plurality of wall sections, vertically arranged staves at the sides of the door-opening of each section; vertical angle-iron casing strips arranged upon the inner edges of said staves with their angles outward; angle-iron cross-pieces arranged across the door-opening of each wall section and riveted to said casing irons, each wall section having a cross-piece at the top and bottom thereof, the bottom cross-piece being arranged with its angle downward, and the top cross-piece being arranged with its angle upward, so that the outwardly projecting legs of the adjacent cross-pieces are brought together; rivets arranged through the

the said outwardly projecting legs of the top and bottom cross-pieces of adjacent wall sections; and hoops for wall sections arranged to embrace said cross-pieces, as specified.

5. In a silo, the combination with the vertically arranged staves at each side of the door-opening, of vertical angle-iron casing strips arranged upon the inner edges of said staves with their angles outward; cross-pieces 10 arranged across the door-opening riveted to said casing strips; lugs punched in from said cross-pieces to engage the inner sides of said casing strips; bolts arranged through said cross-pieces and staves; and bushings for said 15 bolts arranged in said staves, as specified.

6. In a silo, the combination with the vertically arranged staves at each side of the door-opening, of vertical angle-iron casing strips arranged upon the inner edges of said 20 staves with their angles outward; cross-pieces arranged across the door-opening riveted to said strips; lugs punched in from said 25 cross-pieces to engage the inner sides of said casing strips; as specified.

7. In a silo, the combination with the vertically arranged staves at each side of the door-opening, of vertical angle-iron casing strips arranged upon the inner edges of said 30 staves with their angles outward so that 35 their legs overlap the staves; cross-pieces arranged across the door-opening riveted to said casing strips; bolts arranged through said cross pieces and staves; and bushings for said bolts arranged in said staves, as specified.

8. In a silo, the combination with the vertically arranged staves at each side of the door-opening, of vertical angle-iron casing strips arranged upon the inner edges of said 40 staves with their angles outward so that their 45 legs overlap the staves; and cross-pieces arranged across the door-opening riveted to said casing strips, as specified.

9. In a silo, the combination with a door 50 casing, of doors adapted to close onto the inside of said casing; latches pivoted on said doors having cam-shaped portions adapted to engage the outside of the door casing whereby the doors may be clamped into position

under tension, said latches having handles 50 adapted to serve as steps of the ladder, when in their engaging position; stop plates on said doors; and inwardly projecting lugs on said latches adapted to engage said stop plates whereby the said latches are supported in a 55 horizontal position to serve as steps and their upward movement limited, as specified.

10. In a silo, the combination with a door casing, of vertically arranged staves at each side of the door opening, of vertical angle-iron casing strips arranged upon the inner edge of the staves with their angles outward 60 so that their legs overlap the staves; cross pieces arranged across the door opening riveted to said casing strips; doors adapted to 65 close onto the inside of said casing; latches pivoted on said doors having cam-shaped engaging portions adapted to engage the outer legs of said angle-iron casing strip whereby the doors may be clamped into position 70 under tension, as specified.

11. In a silo, the combination with a door casing, of doors adapted to close onto the inside of the said casing; latches pivoted on 75 said doors having cam-shaped engaging portions adapted to engage the outside of said door casing, whereby the doors may be clamped into position under tension; stops for said doors; and inwardly projecting lugs on said latches adapted to engage said stops 80 whereby the latches are supported in a horizontal position to serve as steps.

12. In a silo, the combination with a door casing, of doors adapted to close onto the inside of said casing; latches pivoted on said 85 doors having cam-shaped portions adapted to engage the outside of the door casing whereby the doors may be clamped in position under tension; and stops for limiting the movement of said latches.

In witness whereof, I have hereunto set my hand and seal in the presence of two witnesses.
